UNITED STATES PATENT OFFICE.

FRANKLIN A. SMITH, JR., OF PROVIDENCE, RHODE ISLAND.

BUTTON.

SPECIFICATION forming part of Letters Patent No. 293,531, dated February 12, 1884.

Application filed November 21, 1883. (No model.)

To all whom it may concern:

Be it known that I, FRANKLIN A. SMITH, Jr., a citizen of the United States, residing at Providence, in the county of Providence and State of Rhode Island, have invented certain new and useful Improvements in Buttons; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention relates to garment-buttons; and it consists, essentially, of a button composed of a metallic front, having a projecting apertured neck or shank and a staple provided with an enlarged head adapted to be rigidly secured within said neck during the process of manufacture, thereby forming, when thus completed, a pronged button having a slightly-raised bead around the lower edge of said neck, the prongs of the button at the 25 same time depending through the shank thereof and at a distance from said bead, thus forming a broad attaching-surface, the whole adapted to be secured to garments or other articles of wearing-apparel by any well-known device 30 or means.

In the annexed sheet of drawings, (made greatly enlarged,) Figure 1 represents a vertical central section through my improved button complete. Fig. 2 represents a plan view of a front disk having a perforated oval shank. Fig. 3 represents a central section through the same on line $x-x$. Fig. 4 represents a blank adapted to be bent to form the staple shown in Fig. 4 $\frac{1}{2}$, and again shown rigidly secured within the shank of the button in Fig. 1. Fig. 5 represents a method of securing the staple within the shank by means of movable dies.

In carrying out my invention, A in the 45 drawings represents a button complete constructed according to my improvement, and consisting of the front or disk, a , having a shank or neck, a' , the lower or attaching side

thereof being provided with openings a^3 , for receiving the prongs b' of the staple b . The 50 head of the latter is rigidly secured within the shank a' during the process of manufacturing the button. For the purpose of illustrating a method of effecting this, I have represented in Fig. 5 a series of dies, H E and F F', the latter dies being in halves and adapted to embrace the shank a' of the button. Now, upon pressure being imparted to these 55 dies they are forced toward each other, thereby slightly compressing the shank, the lower 60 side thereof at the same time being slightly expanded, and forming thereby the bead or projection a^2 around the lower edge of said shank, as fully shown, the head of the staple being thereby firmly retained therein. In 65 the drawings I have represented both oval and round shanks in their cross-section. The staples, as represented, have a head projecting beyond the prongs b' , as shown at b^4 , thereby forming, when secured within the button- 70 shank, a corresponding enlarged retaining-surface against the fabric, &c., when secured thereto.

I am aware that it is not new to provide buttons with two or more attaching-prongs, 75 and I therefore do not claim such, broadly; but

What I claim, and desire to secure by Letters Patent, is—

The garment-button A herein described, 80 consisting of the front a and staple b , the former being provided with the neck or shank a' , the face thereof having openings a^3 therein, said neck also adapted to receive the convex-headed staple b , the latter being rigidly secured therein by suitable means during the process of manufacture, and forming a bead, a^2 , around the lower edge of the shank and the bearing-surfaces f outside the prongs b' , substantially as shown and set forth. 85 90

In testimony whereof I have affixed my signature in presence of two witnesses.

FRANKLIN A. SMITH, JR.
